(57) **CLAIM**

The ornamental design for a body cleaner, as shown and described.

DESCRIPTION

FIG. 1 is a perspective view of a body cleaner showing our new design;

FIG. 2 is another perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is a partially enlarged view of FIG. 1;

FIG. 10 is a partially enlarged view of FIG. 4; and,

FIG. 11 is a partially enlarged view of FIG. 7.

The broken lines in FIG. 8 depict portions of the article that form no part of the claimed design. The broken lines showing the enlargements in FIGS. 1, 4, 7, and 9-11 form no part of the claimed design.

1 Claim, 11 Drawing Sheets
